UNITED STATES PATENT OFFICE.

JAMES CARRUTHERS, OF NEW YORK, N. Y.

SHEET-ADJUSTING APPARATUS.

1,055,257.

Specification of Letters Patent.

Patented Mar. 4, 1913.

Application filed February 5, 1910. Serial No. 542,357.

To all whom it may concern:

Be it known that I, JAMES CARRUTHERS, a subject of the King of England, residing in the borough of Manhattan, in the county 5 of New York and State of New York, have invented certain new and useful Improvements in Sheet-Adjusting Apparatus, of which the following is a specification, reference being had therein to the accompanying drawing.

My invention relates to improvements in sheet adjusting apparatus and is particularly adapted for and illustrated in its application to an automatic playing piano.

15 In the accompanying drawings I have illustrated in Figure 1 in elevation, a pair of spools upon which the perforated sheet music of an automatic piano is fed over a suitable tracker board in combination with 20 my automatic adjustment device. Fig. 2 is a plan view of the tracker board with part broken away showing part of the sheet of music, Fig. 3 is a vertical cross section of the same on the line 3—3 of Fig. 2.

25 4 is a suitable framework in which the spools and tracker board are mounted and 5 is the tracker board provided with the usual perforations adapted to register with the perforations in the sheet music 6.

30 7 is a pneumatic having a movable partition 8 in communication with a suitable pneumatic which exhausts the chambers 9 and 10 through the same by the tube 11. 12 is a rod pivotally connected to said partition 8 and fastened to the tracker board.

35 5. The tracker board is provided with valve mechanism at opposite sides comprising the slide members 13—13' adapted to slide freely within the grooves 14—14' and held within the same by the springs 15—15'. These slides are held normally in the position shown in the drawing by the springs 40 16—16' and are sufficiently far apart to lightly engage the sides or outer edges of 45 the perforated sheet 6.

17 is a suitable tubular connection extending from the valve on the left side of the tracker board to the left side of the pneumatic and 17' is a similar tube connect-

ing the valve on the right side of the tracker 50 board with the right side of the pneumatic. From this it will be seen that if the sheet slides laterally on the tracker board so as to bring the perforations therein out of register with the perforations in the tracker 55 board, the slide member in the direction in which the sheet moves, yields through the resiliency of its spring and the slide on the opposite side follows the sheet thereby exposing the tube such as 17 or 17' as the case 60 may be, to the atmosphere, the result being that the air is drawn through said tube into one side of the pneumatic which thereupon shifts the partition 8 operating the rod 12 which shifts the tracker board until the perforations of the same register with the perforations in the sheet. It will be readily understood that when the sheet is running true the tubes 17—17' are both equally covered 65 and the pressure on either side of the partition 8 of the pneumatic is equal, so that everything is perfectly balanced. As soon as the sheet shifts, however, air is drawn into that side of the pneumatic opposite to the direction in which it shifts thereby causing the tracker board to follow the sheet 70 until registry is restored.

75 Of course it will be understood that various modifications may be made without departing from the spirit of the invention 80 as set forth in the claims.

Having described my invention, what I claim as new, and desire to secure by Letters Patent is:

In an apparatus of the class described, a 85 pneumatic, a tracker, a sheet adapted to pass over the surface of said tracker, passage-ways through said tracker terminating in ports, a reciprocating slide valve mounted for sliding movement longitudinally of said tracker for opening and closing said ports, at each side of said sheet, guide-ways for each of said valves, means for maintaining contact between said slide valves and the opposite edges of said sheet, 90 said slide valves in the normal position of said sheet being in position to close said ports and one of said ports being opened

by one of said slide valves by the transverse divergence of said sheet from its normal position, connections between said passageways and said pneumatic, and means for adjusting the relation between said sheet and said tracker when either of said slide valves is actuated.

In testimony whereof I affix my signature in presence of two witnesses.

JAMES CARRUTHERS.

Witnesses:

THOMAS A. HILL,
LOUISE ENDERLE.
